UNITED STATES PATENT OFFICE.

EMILE DOR-DELATTRE, OF LIEGE, BELGIUM.

MEANS FOR PROTECTING OPERATIVES OF ZINC AND ANALOGOUS FURNACES FROM HEAT, FUMES, AND DUST.

No. 921,375.

Specification of Letters Patent.

Patented May 11, 1909.

Application filed August 12, 1908. Serial No. 448,223.

To all whom it may concern:

Be it known that I, EMILE DOR-DELATTRE, engineer, subject of the King of Belgium, residing at Liege, Belgium, have invented certain new and useful improvements in means for protecting the operatives of zinc and other analogous furnaces from heat, fumes, and dust; and I do hereby declare the following to be a full, clear, and exact description of the invention, such as will enable others skilled in the art to which it appertains to make and use the same.

Of all metallurgical furnaces, those which evolve the most heat, fumes and dust, are the reducing furnaces employed in the zinc industry. Under the influences of these three agents, heat, fumes, and dust, the health of the operatives rapidly becomes impaired.

The arrangement which is the subject of the present invention has for its object to provide means for protecting the operatives almost completely from the heat, and completely from the fumes and dust, without impeding either the progress or the rapidity of the reducing operations. On the contrary, the said means, by protecting the operatives, facilitates their work in the operations of extracting the zinc, and cleaning and charging the retorts.

This appliance permits: First. Of any one single line of retorts, *i. e.* that in which the work is taking place, being uncovered or exposed while completely isolating the workman from all the others; a fixed or stationary opening is thus provided for work of considerable duration. Second. Of the provision of an opening of any desired height or size, which may be rapidly shifted or brought in front of the different lines of retorts; such movable opening thus facilitating the performance of rapid work or operations of short duration. In both conditions, the workman is completely protected or shielded from the heat, fumes and dust which are evolved from the rows of covered retorts; he is also completely protected against the fumes and dust which are evolved from the row of uncovered retorts; and further, the effects of the heat evolved from this row of uncovered retorts are considerably mitigated.

The accompanying drawings represent an appliance or protective screen of the kind described.

Figure 1 is a part front elevation of a zinc

furnace provided with the protecting screen. Fig. 2 is a transverse section on A—A through the panels constituting this screen and through the guides of the latter. Fig. 3 is a transverse section through the zinc furnace on B—B.

The appliance consists of a movable screen, formed by a number of panels *a* (six in the example represented). Each of these panels *a* (Figs. 2 and 3) is formed of a treble thickness of sheet-iron *m*; between the first and the second plates *m* is interposed a hard layer of asbestos *n* while between the second and the third plates *m*, (the latter being preferably perforated) there is an air space *p*. This alternation of layers of air and asbestos with the metallic plates has the effect of rendering the panels *a* practically impervious to heat. Each end *q* of the panels *a* is adapted to work in a vertical guide *b*, formed in the arrangement shown, by two channel-sectioned members connected by an iron plate. The lower panel *c* is a fixture to the guides *b* and serves to support the other superimposed panels *a*, of which the ends *q* can slide in the guides *b*. Chains *d*, passing over pulleys *e* are fixed at the one end to the guides *b*, and at the other end to the ordinary trolley *f*. This trolley *f*, guided in any suitable manner, is connected at its end, to a hydraulic ram *g* through the medium of two chains *h*. It follows that when the hydraulic ram *g* is put into operation, the trolley *f* is caused to move in one direction or the other, and effects the raising or lowering of the protecting screen composed of the panels *a* and *c*.

The chains *d* and *h* are connected to the trolley *f* by means of screwed rods *o* which permit of adjustment of the tension of the said chains respectively.

The employment of the trolley *f* and the arrangement of the adjusting rods *o* admit of the operation of the several panels or elements of the screen by a single hydraulic machine since the provision of the means for adjusting the chains admits of the adjacent panels being brought into the same horizontal line.

Above the movable screen is a fixed screen 1, behind which the whole of the movable screen can be raised and thus completely hidden from view (see left hand side of Fig. 3). While when the movable screen is lowered the space at the back of the fixed

or standing screen constitutes, as it were, a shaft of considerable sectional area which is connected up with a suitable exhausting system.

5 The openings in the protecting screen, that is to say, the spaces which are formed by the vertical separation of the horizontal panels, in order to admit of access being obtained to any desired row of retorts, are obtained by the use of steel pins, which are introduced, according to circumstances, into certain of the series of holes *r* in the guides *b* and in the ends of the extremities *q* of the panels *a*; or in the holes *s* made in the panels *a* and in the framing *k* of the furnace.

10 The methods of working the appliance are as follows:—To uncover the upper row of retorts, the movable screen is allowed to fall to the ground (see Fig. 1 and Fig. 3, right

20 hand side). Then, assuming the distance between the upper edge of the top panel *a* of the movable screen, when lowered to this position, and the lower edge of the fixed screen *l* has been arranged so that the said 25 distance shall be equal to, or slightly greater than, the height of a row of retorts *i*, it is evident that this upper row of retorts will be completely uncovered and rendered accessible, while all the other retorts in the furnace 30 will be covered by the panels of the movable screen.

To uncover any intermediate row of retorts below the top one, the movable screen is first, by the aid of the hydraulic machine 35 *g*, lowered to the ground and then raised a distance equal to the height of one row of retorts. The panel *a* which comes above the opening to be made, is then fixed to the framing *k* of the furnace by inserting the 40 stop pins through the holes *s*, in the fixed guide or like members of the structure and then the screen is again lowered. The panel *a* which is fixed to the framing *k* of the furnace by the pins, cannot fall, and consequently 45 serves to support the panels above it, so that they also are prevented from falling. The vertical guides *b* therefore only take with them, in their descent, those panels which rest on the bottom panel *c*, and which 50 fall away from the temporarily fixed or pegged-up panels.

When the lower panel *c* comes to rest on the ground, the open space or clearance that is thereby presented between the panel 55 which is fixed to the framing *k* and the panel which is immediately beneath it, is equal to the height the appliance had been previously raised, and registers with the row of retorts to which it is desired to obtain access.

60 To uncover the bottom row of retorts, it is only necessary to raise the entire movable screen to the desired height.

If, in place of the stationary or fixed openings obtained by the methods of working 65 above referred to, it is desired to obtain an

opening capable of being moved in front of the furnace, the following is the method adopted. By the operation in the second case, a stationary or fixed opening is first formed of the height, and in the position desired. This opening having been obtained, the supporting pins are passed under the fixed panels and through the holes *r* in the vertical guides *b* and the pins fixed to the framing *k* are removed. If then the hydraulic ram *g* is put in operation, the entire screen will respond to its movement by rising or falling as the case may be, while the space between the two separated sets of panels remains always the same, and the screen with this opening in it can be moved vertically in front of the furnace and arrested in any position by the working of the hydraulic machine.

When the movable screen is not required in front of the furnace, it is completely raised and entirely disappears behind the fixed screen *l*.

It is evident from the foregoing that this appliance, which permits of working in any row of retorts, places the workmen completely under shelter from the heat, fumes and the dust issuing from the furnace.

It is also evident that the workman, who uses for his work, tools which are heavy and difficult to manage, can support such tools on the top edge of the panel that comes immediately below the opening in the movable screen and below the line of the uncovered retorts. This work is thus considerably facilitated by this support, and other or additional supports of any form are rendered unnecessary.

Having fully described my invention, what I desire to claim and secure by Letters Patent is:—

1. The combination with a zinc or analogous furnace, of a screen extending across one end of the furnace retorts and comprising a plurality of panels, arranged one above the other, and adjustable means for supporting one or more of said panels out of contact with the other panels to provide an opening in the screen at any desired point in the height thereof, and means for raising and lowering the screen without varying the relation of the separated panels.

2. A protecting device for zinc and other analogous furnaces consisting of a screen composed of a number of separate superimposed parts adapted to be separated from one another to expose one or more rows of retorts, two vertical guides for the other parts of the screen connected with the lower member of the screen, said guides being connected to a contrivance which admits of raising or lowering the screen in front of the furnace or retorts.

3. A protecting device for zinc and other analogous furnaces, consisting of a screen

composed of a number of separate superimposed parts adapted to be separated from one another, and whose ends are adapted to be fixed to the framing of the furnace so as 5 to form an opening in the screen of the required size, in front of one of the rows of retorts.

4. The combination with a zinc or analogous furnace, of a screen extending across 10 one end of the furnace retorts and comprising a frame, a plurality of panels adjustably supported in said frame, one above the other and normally contacting one with another throughout the height of the screen, means 15 for maintaining one or more of said panels in adjusted position to provide an opening between any two thereof, and means for moving the frame and all of the panels vertically without varying the relation of the 20 separated panels.

5. A screen for zinc and analogous furnaces composed of a number of separate superimposed parts adapted to be separated from one another, a pair of vertical guides to 25 which the lower separate part of the screen is fixed, a contrivance connected to said guides for raising and lowering the screen in front of the furnace, and means for fixing the ends of the separate parts of said screen to the framing 30 of the furnace so as to form an opening of the required size in front of one of the rows of retorts.

6. A screen for zinc and analogous furnaces composed of a number of separate superimposed parts adapted to be separated from one another, a pair of vertical guides to 35 which the lower separate part of the screen is fixed, a contrivance connected to said guides for raising and lowering the screen in front of the furnace, and means for fixing the separate parts of said screen to the guides so as to 40 form an opening, which together with the screen, can be moved in front of the furnace or the retorts thereof.

45 7. A protective device for zinc and analogous furnaces consisting of a screen composed of a number of separate superimposed parts adapted to be separated from one another, a pair of vertical guides to which the lower 50 separate part of the screen is fixed, and a single slide or trolley connected by chains or the like to the guides of one or more screens, and also connected to the lifting or lowering means of the screens.

55 8. A protective device for zinc and analogous furnaces consisting of a screen composed of a number of separate superimposed parts

adapted to be separated from one another, a pair of vertical guides to which the lower separate part of the screen is fixed, and a single slide or trolley connected by chains or the like to the guides of one or more screens and also connected to the lifting or lowering means of the screens, said chains or the like being connected to the slide or trolley by adjustable screwed rods, so as to enable the separate parts of adjacent screens to be maintained in the same horizontal plane. 60 65

9. A protective device for zinc and analogous furnaces, consisting of a screen composed of a series of superimposed and separable parts adapted to be raised and lowered in front of the furnace, and above which a fixed screen is arranged, adapted to cover-up the movable screen when the latter is raised. 70 75

10. A protective device for zinc and analogous furnaces, consisting of a screen composed of a series of superimposed and separable parts adapted to be raised and lowered in front of the furnace, and above which a fixed screen is arranged, adapted to cover-up the movable screen when the latter is raised, and the space formed by said fixed and movable screens being connected-up with an exhausting system. 80 85

11. A screen for zinc and analogous furnaces consisting of a series of superimposed and separable parts composed of three walls lying one behind the other, and between the middle and one of the outer walls of which a layer of asbestos is interposed, while the middle wall is separated from the other outer wall by an air space. 90

12. A screen for zinc and analogous furnaces consisting of a series of superimposed and separable parts composed of three walls lying one behind the other, the outer one of which is perforated, and between the middle and one of the outer walls of which a layer of asbestos is interposed, while said middle wall and the other outer wall are separated by an air space. 95 100

13. The herein-described protective screen for furnaces consisting of three superimposed metal plates, and a body of asbestos arranged between the rear and middle plates, the latter and the front plate being separated by an air space. 105

In testimony whereof I affix my signature in presence of two witnesses.
